UNITED STATES PATENT OFFICE.

LAWRENCE E. JOHNSON, OF WINTHROP, AND EDWARD ERICKSON, OF LYNN, MASSACHUSETTS, ASSIGNEES TO VICTOR SHOE MACHINERY CO. OF BOSTON, MASSACHUSETTS, A CORPORATION OF MASSACHUSETTS.

SEWING-MACHINE.

1,183,147.

Specification of Letters Patent. Patented Mar. 23, 1915.

Application filed May 19, 1913. Serial No. 768,671.

To all whom it may concern:

Be it known that we, LAWRENCE E. JOHNSON, a citizen of the United States of America, and a resident of Winthrop, in the county of Suffolk and State of Massachusetts, and EDWARD ERICKSON, a subject of the King of Sweden, and resident of Lynn, in the county of Essex and State of Massachusetts, have invented certain new and useful Improvements in Sewing-Machines, of which the following is a specification.

This invention relates to improvements in shoe-sewing machines, and more especially to lockstitch wax thread machines for stitching outer soles of shoes to the welt, and it consists in certain novel features of construction and arrangement of parts which will be readily understood by reference to the description of the drawings and to the 20 claims hereinafter given.

Of the drawings: Figure 1 represents a plan of a sewing machine embodying the invention. Fig. 2 represents a front elevation of the same. Fig. 3 represents an elevation 25 of the left end of the same. Fig. 4 represents an elevation of the right end of the same. Fig. 5 represents a vertical section of the same, looking to the right, the cutting plane being on line 5—5 on Fig. 1. Fig. 6 represents a vertical section of the same, 30 looking to the left, the cutting plane being on line 6—6 on Fig. 1. Fig. 7 represents an elevation of the needle and awl driving members and showing the looper hook and the cam for operating it. Fig. 8 represents a plan of the rear end of the looper support and showing in section a portion of the cam for operating the looper. Fig. 9 represents a sectional detail of the shuttle cap 35 locking mechanism, the cutting plane being on line 9—9 on Fig. 3. Fig. 10 represents a 40 transverse section of the same, the cutting plane being on line 10—10 on Fig. 9. Figs. 11 and 12 represent details of the looper to be hereinafter described.

Similar characters designate like parts throughout the several figures of the drawings.

In the drawings, 20 is the base of the 50 machine adapted to be secured to a column and having the end frames 21 and 22 provided with bearings for the revoluble shaft

23. The revoluble shaft 23 has the driving wheel 24 secured to one end thereof while to its opposite end is keyed the cam disk 25. Interposed between the side frames 21 and 22 and keyed to the shaft 23 are the cam disks 26 and 27. To the inner side of the side frame 21 is secured the work support 28 which may be of any well-known 60 construction, the securing means consisting of the bolts 29—29. The side frame 21 has also formed upon its inner face a race 30 for the shuttle 31 which is driven by a plate 31 having a shuttle engaging lug 312 and 65 provided with a shank 32 having keyed to its outer end a gear 33 partially surrounded by the flange 34 formed on the outer face of the side frame 21. Meshing with the gear 33 is a gear segment 35 formed upon the end 70 of a lever 36 pivoted at 37 to the side frame 21, the opposite end or arm of said lever being articulated at 38 to a connecting rod 39 pivotally connected to the cam disk 25 by the stud 40. When the cam disk 25 is 75 rotated in the direction of the arrow *a* on Fig. 3 an oscillating movement will be imparted to the segment 35 by the connecting rod 39. It will be observed that the total length of the operating arm of the lever 36 80 and the connecting rod 39 between the centers of the stud 40 and pivot 37 is greater than the direct distance between said points so that it is impossible for these members to come into alinement under any condition. 85 This oscillation of the segment 35 will impart the required movement to the plate 31 and through the lug 312 to the shuttle 31. The shuttle 31 is provided with a cap 41 pivoted at 42 to the side frame 21, said cap 90 being adapted to be moved about its pivot to permit the removal of the shuttle 31 when it is desired to renew the bobbin. Normally the cap 41 is retained in the position shown in the drawings by the locking member 43 95 extending therefrom into a slot in the extension 44 of the side frame 21. In a bearing in the extension 44 is a member 45 having a depression in its inner end into which extends the outer end of the member 43 which 100 is provided with a pin 46 normally engaging a notch 47 in the member 45 to limit the oscillation of the member 45 about its axis. A portion of the wall of said depression is

cut away to permit the removal of the locking member 43. The outer end of the member 45 has secured thereto by a nut 431 a handle 48 by which said member 45 may 5 be moved sufficiently about its axis to cause the cut-away portion thereof to register with the slot in the arm 44 and thus permit the locking member 43 to be removed from the depression in the end of the member 45 and 10 the cap 41 to be moved upwardly about its pivot 42 so that the shuttle 31 may be removed.

The cap 41 is provided with a chamber 56 adapted to receive a heater the heat from 15 which will keep the wax thread T within the shuttle 31 in condition for use.

The frame 22 is provided with two parallel studs or pins 60, 61, on which is mounted a movable frame 62. This frame has pivoted to the lower end thereof at 63 an oscillating slotted lever 64 the lower end of which is provided with a roller 65 extending into a cam path 66 in the periphery of the cam disk 27. In the slot 67 of the lever 25 64 is a fulcrum block 68 pivotally mounted in a forked member 69 having a shank 70 extending through a straight slot 71 in the frame 22 and also through a slot 72 in a hand lever 73 pivoted at 74 to the end frame 20 22. That portion of the shank that travels in the slot 71 is flattened to fit said slot and be guided thereby. The shank 70 is surrounded by washers 75 between which is a spring 55 tending to retain the lever 73 30 35 against the flange around the slot 71, the friction thereon being sufficient to lock the lever 73 in adjusted position. The washers 75 and spring 55 are retained in position by means of the nut 76. It is obvious 40 that when the cam disk 27 rotates, the cam path 66 thereof will operate upon the roller 65 to actuate the lever 64 about its fulcrum thereby moving the frame 62 a given distance, this distance depending upon the position of the fulcrum pin 77. The inclination of the slot 71 conforms to that of the lever 64 to permit the free movement of the forked member 69 lengthwise of the lever 64 without binding thereon.

50 By means of the handle 73 the position of the fulcrum block 68 may be changed at will to secure any desired degree of feed. It is obvious that the shank 70 will be moved in the slot 71 during the movement of the hand 55 lever 73 about its pivot 74, and when adjusted the friction on the lever will be sufficient to retain it in this position. When desired the nut 76 may be adjusted so that the lever 73 will be positively locked so that 60 a continuously uniform feed of the work will be obtained. The frame 62 has a long bearing formed therein in which is mounted the shaft 80 having pinned to its outer end a collar 81 provided with an ear between

which and a pin on the upper end of the frame 62 is interposed a spring 82 adapted normally to retain the needle guide 83 secured to the opposite end of the shaft 80 in proper relative position to the needle 84 carried by the needle support 85. The guide 70 83 is normally positioned by the pin 833 in the hub thereof bearing against a wall of said needle support 85, said pin being retained in this contacting position by the spring 82. The needle guide 83 is provided 75 with a slot 83* at its outer end which retains the oil therein and serves as a means for lubricating the needle as it moves through said guide in either direction. When the needle 84 is operating the guide 83 is caused 80 to move with the needle support 85 by the tension of said spring 82 until the ear on the collar 81 comes into contact with the pin 811, when further movement of the guide 83 will be prevented.

85 The needle support 85 has a gear segment 86 formed thereon and is provided with a tubular sleeve 86* surrounding the shaft 80 in the long bearing in the frame 62 and about the axis of which it is adapted to be 90 oscillated by the lever 87 having formed thereon at one end a gear segment 88 meshing with the gear segment 86. The teeth of the gear segment 88 are of sufficient length to permit the teeth of the gear segment 86 95 to remain constantly in mesh during the movement of the frame 62 in either direction. The lever 87 is pivoted at 89 to the frame 21 and is provided at its rear end with a roller 90 in the cam path 91 formed in the 100 cam disk 26. During the rotation of the disk 26 the cam path 91 operates upon the roller 90 to give the required movement to the needle segment at the proper time. The needle support 85 has also secured thereto 105 the awl 911 positioned thereon so as to enter a slot in the work support 28 and the work supported thereby during a portion of the oscillation of said needle support, this awl being in the same vertical plane with the 110 needle 84.

The lever 87 is provided on one side with a cam extension 92 adapted to act upon a roller 93 on a bell crank lever 94 pivoted at 95 to the side frame 21 beneath the shuttle 115 race 30. The forward end of the lever 94 has secured therein a looper hook 96 and a spring 97 is provided to retain the roller 93 in contact with the cam extension 92 at all times. The lever 87 is provided with an upwardly extending arm 98 to the upper end of which is pivoted a link 99 the opposite end of which is articulated to a loop spreader 100 pivoted at 101 to the hub 102 formed on the upper end of the movable frame 62. The forward end of the spreader 100 is curved downwardly and rearwardly as indicated in 120 Fig. 6 and its left hand edge is inclined as 125

shown in Fig. 2. This mechanism provides a simple means for spreading the loop of thread at the proper time for the hook of the shuttle 31 to enter the same.

5 The thread *t* is drawn from any suitable source of supply and passes over a fixed rod 103 extending from one side frame 21 to the other 22, a pin 104 extending outwardly from this rod 103 positioning the 10 thread *t* thereon and preventing it from slipping lengthwise thereof. The thread *t* then passes around a pin 105 secured to the thread lock cam lever 106 which is pivoted at 107 and has at its rear end a roller 108 in 15 the cam path 109 formed in the right hand side of the disk 27. The thread *t* passes from the pin 105 over a stationary pin 110 in the side frame 22 and then through slots in two downwardly extending arms 111 of 20 a forked member 112. The thread *t* passes from one arm 111 to the other arm 111 under a stud or pin 113 projecting horizontally from the side of the forward end of the lever 108. From the forked member 112 the 25 thread *t* passes through a hole 114 in the movable frame 62 to an eye 115 on the side frame 22 and thence into the wax pot 116 secured to the side frames 21 and 22 by the screws 117. To the front wall of the wax 30 pot 116 is clamped, by means of the clamp screw 118, a support 119 having two arms 120 extending into the wax pot 116, each arm 120 being provided with a sheave 121 around which the thread *t* passes through 35 the liquid wax in said pot 116. Having passed through the wax pot the thread *t* extends through an eye 122 secured to the end frame 21 and then over a sheave 123 revolute about a stud on the end frame 21 40 and around a sheave 124 revolute about a stud secured to the end of a takeup lever 125 pivoted to the frame 21 at 126 and having articulated thereto at 127 a link 128, the opposite end of which is pivotally connected 45 to a cam lever 129 pivoted at 130 to the frame 21. The free end of the lever 129 is provided with a roller 131 in a cam path 132 formed in the side of the disk 25, said path being provided with the necessary throws to 50 actuate the takeup lever 125 at the proper time to take up the slack in the thread. The thread *t* passes from the sheave 124 on the takeup lever 125 to the eye 51 in the looper member 127* secured to the forked member 55 128*, the downwardly extending arms 129* of which straddle and are pivoted to the squared end 130* of an oscillating member 131*. This member 131* has a bearing in the end frame 21 and to its outer end is secured an arm 132* between the outer end of which and an eye 133 in the base 20 is interposed a spring 134. The rearwardly extending arm 135 is provided with a roller 136 positioned in the cam path 137 in the pe-

riphery of the disk 26 and other rollers 138 65 held in contact with the periphery of the disk 26 by the spring 133. The periphery of the disk 26 is provided with a throw 139 adapted in the rotation of said disk to oscillate said member 130*—131* about its axis 70 while the throw 140 in the cam path 137 is rocking the member 135 about the axis of the pivot pin 141, the combined action of these throws forming the necessary loop around the hook of the needle 84 after it 75 has passed through the work and is extending through the slot of the work support 28. The extreme upper end 126* of the looper 127* is provided with an eye 51 and a finger 52 extending beyond the end of said eye 51. 80 The eye 51 and finger 52 form a slot in which the needle 84 is temporarily positioned during the formation of the loop.

The loop spreader 100 operates in the same plane with the hook of the shuttle 31 85 and when the barb of the needle 84 has drawn the loop of thread through the work the tapered end of said spreader will enter between the two portions of the thread on said barb and spread them apart so that the 90 shuttle-hook will be sure to enter. When the needle 84 has passed through the work so that its barbed end extends below the work support 28 the looper hook 96 will also be moved downwardly so that when the 95 looper 126 operates the thread *t* will not only be placed upon the barb of the needle 84 but it will also be carried around the hook 96 so that a given amount of thread will be always measured off to be carried 100 through the work by the needle 84 preparatory to its coating with the shuttle in the formation of the stitch. Owing to the pivotal connection of the looper support 128 whereby it may be tilted in either direction by the cams 139 and 140, the looper 126 will have imparted to it an orbital movement in a path encircling that in which the needle 84 moves and also about the looper hook 96, the cams 139—140 being so constructed and timed that this movement will occur when the needle has passed through the work and lies within the orbit of the looper. 105

As has been stated, the needle 84 and the awl 911 are in the same vertical plane and oscillate about the same axis so that the entering of the needle 84 into the hole in the work formed by the awl is always assured and no opportunity is afforded for them to 110 get out of register.

The needle and awl support 85 is mounted on a movable frame 62 and when the awl is in the work the latter may be fed relative to the work support, the length of feed being determined by the handle 73, it being obvious that by means of the devices controlled by said handle a change in the feed 115 120 125 125

may be obtained at any time while the machine is running.

It will be seen that by the construction shown and described, a very compact sewing machine is provided in which the parts are reduced to a minimum. The machine is particularly adapted to be used by unskilled labor such as shoe repairers, although it may be used equally as well on new work.

10 It is believed that the operation and many advantages of this sewing machine will be fully understood from the foregoing description.

Having thus described our invention, we 15 claim:

1. In a shoe-sewing machine, a stitch-forming mechanism consisting of a needle, an oscillating shuttle, driving mechanism for said shuttle, a loop-forming mechanism, 20 needle-operating mechanism, including a cam-controlled lever, a tapered spreader mounted to operate in a plane parallel to the needle, and connections between said cam-controlled lever and spreader adapted 25 to cause the latter, by the operation of the former, to be oscillated to expand the loop held by the barb of the needle as the shuttle coöperates therewith.

2. In a shoe-sewing machine, the combination of a needle; operating mechanism therefor including a cam-controlled lever; a loop-spreader comprising a tapered finger mounted to operate in a plane parallel to the needle and having its operating end 35 curved rearwardly; a support therefor; and means operable by the cam-controlled lever for moving the spreader transversely of the loop held by the barb of the needle.

3. In a shoe-sewing machine, the combination of a needle; operating mechanism therefor including a cam-controlled lever; a shuttle, a pivoted loop spreader comprising a finger mounted to operate in a plane with the hook of the shuttle and parallel to the 45 needle, said finger having a tapered end curved rearwardly; and means connected with said cam-controlled lever for moving said spreader about its pivot and causing it to expand the loop held by the barb of the 50 needle as the shuttle coöperates therewith.

4. In a shoe-sewing machine, a stitch-forming mechanism consisting of an oscillating needle, operating mechanism therefor including a cam-controlled lever, a shuttle mechanism, a loop forming mechanism, a finger having a pivot parallel with the axis of oscillation of said needle and provided with a wedge-shaped operating end adapted to expand the loop as the shuttle 60 coöperates therewith, the side adjacent said needle being parallel thereto, a support for said finger, and means operable by said cam-controlled lever for moving said finger about its pivot and causing it to expand the loop

held by the barb of the needle as the shuttle 65 coöperates therewith.

5. In a shoe-sewing machine, a stitch-forming mechanism consisting of a needle, operating mechanism therefor including a cam operated arm; a shuttle mechanism, a loop forming mechanism, a pivoted finger having a wedge-shaped operating end and operable in a plane parallel to the plane of movement of said needle when forming a stitch, and a link between said finger and 75 arm whereby during the operation of the needle said finger will be moved by said arm to cause its wedge-shaped operating end to enter the loop held by the barb of the needle and spread said loop as the shuttle coöperates therewith.

6. In a shoe-sewing machine, a stitch forming mechanism consisting of a needle, a shuttle mechanism, a loop forming mechanism, and a looper hook adapted to be retained in a stationary position within the orbit of the looper during the formation of the loop.

7. In a shoe-sewing machine, a stitch forming mechanism consisting of a needle, 90 a shuttle mechanism, a loop forming mechanism, a looper hook adapted to be retained in a stationary position within the orbit of the looper during the formation of the loop; and means for withdrawing said hook prior 95 to the movement of the needle to draw the loop through the work.

8. In a shoe-sewing machine, a stitch forming mechanism consisting of a needle, operating mechanism therefor, a shuttle 100 mechanism, a loop forming mechanism, and a looper hook operable by said needle operating mechanism and adapted to be retained in a stationary position within the orbit of the looper during the formation of 105 the loop.

9. In a shoe-sewing machine, the combination of a needle; a support therefor provided with a gear segment; a cam controlled lever having a gear segment meshing with 110 said needle support gear segment; a pivoted looper hook; means on said lever for moving said hook about its pivot; and a looper adapted to form a loop about said needle and hook.

10. In a shoe-sewing machine, a stitch forming mechanism consisting of a needle, a shuttle mechanism, and a loop forming mechanism combined with a pivoted looper hook movable in a vertical plane and adapted to be moved into the orbit of the looper prior to the formation of the loop and retained in this position until the loop has been completed.

11. In a shoe-sewing machine, a stitch 125 forming mechanism consisting of a needle, a shuttle mechanism, a loop forming mechanism, and mechanism for operating said

needle, combined with a pivoted looper hook, and a cam member operated by said needle operating mechanism adapted to move said hook into its operating position in the orbit 5 of said looper and return it to its normal position, said cam being timed to produce said movements before and after the formation of the loop.

Signed by us at 19 Columbia st., Boston, Mass., this 13th day of May, 1913.

LAWRENCE E. JOHNSON.
